UNITED STATES PATENT OFFICE.

RUSSELL W. EATON, OF BRUNSWICK, MAINE.

SPEED-RECORDING APPARATUS.

SPECIFICATION forming part of Letters Patent No. 694,913, dated March 4, 1902.

Application filed April 17, 1901. Serial No. 56,185. (No model.)

To all whom it may concern:

Be it known that I, RUSSELL W. EATON, a citizen of the United States, and a resident of Brunswick, county of Cumberland, State of

5 Maine, have invented an Improvement in Speed-Recording Apparatus, of which the following description, in connection with the accompanying drawings, is a specification, like letters on the drawings representing like parts.

10 This invention has for its object the production of means whereby the variation in speed of a prime driving member or a motor may be recorded in such a manner that by 15 inspection of the record at the close of the day it may be readily ascertained whether the speed of the prime member has been too high or too low and at what particular period or periods during the day.

20 I have herein shown one practical embodiment of my invention in connection with one well-known form of so-called "watchmen's" 25 clocks, as my invention can be very conveniently used in connection with such a clock.

25 Various novel features of my invention will be hereinafter described, and particularly pointed out in the drawings.

Figure 1 is a view in elevation and partly diagrammatic showing one embodiment of my 30 invention. Fig. 2 is a right-hand end elevation of the mechanism shown at the upper part of Fig. 1, and Fig. 3 is a side elevation of the clock-case and the recording mechanism.

35 For the purposes of this invention the prime driving member may be a motor or one of the driving-shafts of a mill—such, for instance, as shown at A—and I have herein shown such member as provided with a worm a , in mesh with a worm-gear a' , mounted to rotate on a 40 stud a^x , secured to or forming part of a stand or bracket A^x , the said bracket being secured to any suitable and convenient part of the building. The worm-gear has secured to or forming part of it a pinion a^2 , which meshes with 45 a larger gear a^3 , rotatably mounted on a stud a^4 on the bracket, said gear a^3 having projecting from its face and eccentric to the stud a^4 a lug or pin a^5 .

50 In practice the gearing may be so arranged that the gear a^3 will be rotated once in each half-hour, provided the prime driving member A is running at its normal speed.

Instead of the period of time mentioned any other suitable period may be selected in which the gear a^3 is to make one complete 55 revolution.

I have shown in Fig. 1 an electric circuit comprising the wires 3 4 and a battery B or other suitable source of electrical energy, the said circuit having included therein one member 60 of a recording device which is responsive to change in the circuit.

Referring to Figs. 1 and 3, I have shown at C a watchman's clock, which may be of any suitable construction, and one member of the 65 recording device is actuated by or through the clock to be moved thereby at a predetermined rate of speed.

I have found it convenient to use the rotatable dial-sheet c , which forms a part of a 70 watchman's clock, as one member of the recording device, the other member being herein shown as a perforating-pin c' , mounted to rock upon a suitable fulcrum c^2 adjacent the dial and mounted on a supporting-frame c^3 , 75 which latter sustains a suitable electromagnet m , the coils of which are in the circuit, as shown in Fig. 1. The armature m is mounted on the arm which carries the perforating-pin c' , so that when the magnet is energized 80 the said pin will be drawn toward the dial to perforate or indent the same. A suitable spring s , Fig. 3, may be employed to retract the armature when the electromagnet is de-energized.

85 I have provided a circuit-changer to change the condition of the circuit once for every revolution of the gear a^3 , and said circuit-changer may be of any suitable construction. Herein I have shown a fixed terminal t and a 90 yieldingly-mounted contact-pen or coöperating terminal t' , the two terminals in the structure herein shown being normally separated, with the circuit correspondingly open.

A bell-crank b b' , fulcrumed at b^x on the 95 bracket A^x , is arranged with the end of the arm b bearing against the pen-terminal t' , any suitable insulating material being arranged upon the end of the arm b , as at 6, and I prefer to make the shorter arm b' of the bell-crank slightly yielding, said arm projecting into the path of the lug a^5 . Whenever the said lug a^5 is brought into engagement with the arm b' , the gear a^3 rotating in the direc-

tion of the arrow 10, Fig. 1, the bell-crank will be rocked and the circuit will be closed to thereby energize the magnet and cause the recording-pin *c'* to coöperate with the dial *c*. The yielding arm *b'* permits the lug *a'* to snap past the same and quickly release it.

Supposing for the sake of illustration that it is desired to keep a record every half-hour of the speed of the prime driving member *A* and that the dial *c* makes one complete revolution in twelve hours, if the prime member *A* is running at its normal speed the record sheet or dial *c* will be perforated once during every half-hour, giving a permanent speed record, which can be referred to at any time. If the speed of the prime member is below normal for one or more of the successive periods of time, then the perforations on the record-sheet will be more than one-half hour apart, while they will be less than a half-hour apart if the speed of the prime member has been greater than normal.

It will be understood that the watchman's clock will be located in the office of a mill or other manufacturing establishment, as is now usual, and that the circuit-changer and the means for actuating the same periodically may be at a very distant point, the connection between the two separated parts of the apparatus being effected by or through the electric circuit.

It will be manifest to those skilled in the art that various changes may be made in the details of construction without departing from

the spirit and scope of my invention, for the mechanism intermediate the prime driving member and the circuit-changer may be variously constructed, the circuit-changer itself may be of any suitable construction, and it will be obvious that the change in the circuit may be from open to closed condition, or vice versa; but, so far as I am aware, it is broadly novel to provide speed-recording mechanism for a prime driving member or motor in connection with a watchman's clock or similar device.

Having fully described my invention, what I claim as new, and desire to secure by Letters Patent, is—

In a speed-recording apparatus, a clock, an electric circuit, a recorder, one member of which is actuated by the clock, a prime driving member, gearing actuated thereby, a circuit-changer in said circuit operated by said gearing and comprising a fixed terminal, a movable terminal, and an operating member adapted to connect the two terminals, said member being intermittently and yieldingly engaged by said gearing and periodically operated thereby.

In testimony whereof I have signed my name to this specification in the presence of two subscribing witnesses.

RUSSELL W. EATON.
